UNITED STATES PATENT OFFICE.

AUGUST BOUCHERY, OF NEW YORK, N. Y., ASSIGNOR TO WALLACE NOVELTY COMPANY, OF NEW YORK, N. Y., A CORPORATION OF NEW YORK.

DESIGN FOR AN INCANDESCENT ELECTRIC LAMP.

47,217.

Specification for Design.

Patented Apr. 13, 1915.

Application filed December 30, 1914. Serial No. 879,810. Term of patent 14 years.

To all whom it may concern:

Be it known that I, AUGUST BOUCHERY, a citizen of the United States, residing in the borough of Brooklyn, county of Kings, city and State of New York, have invented a new, original, and ornamental Design for an Incandescent Electric Lamp, of which the following is a specification, reference being had to the accompanying drawing, forming a part thereof.

The figure is a perspective view of an incandescent electric lamp showing my new design.

I claim:

The ornamental design for an incandescent electric lamp as shown.

AUGUST BOUCHERY.
